Application September 23, 1936, Serial No. 102,178

48 Claims. (Cl. 178—25)

(Granted under the act of March 3, 1883, as amended April 30, 1928; 370 O. G. 757)

The invention described herein may be manufactured and used by or for the Government for governmental purposes, without the payment to us of any royalty thereon.

This invention relates to printing telegraph machines.

The invention is a further development and improvement based upon our previous application, Serial No. 725,968 filed May 16, 1934, Patent No. 2,128,242, dated Aug. 30, 1938, which relates primarily to printing telegraphy and printing-telegraph equipment constituting in effect a printing-telegraph system wherein exact synchronization between transmitting and receiving processes is effected for each and every signalling impulse by means of reed-operated escapements which time the processes with precision. In this invention we combine certain new elements with the devices previously described to provide a storage receiver or permutation escapement selector and transfer devices operating upon translators as applied to particular forms of printing-telegraph equipment, including new features in keyboard transmitters, printers and related structures as will hereinafter appear.

One of the main objects of this invention is to establish a permuted selection of elements in progression under the control of a reed-operated escapement and to lock up that selection as a storage receiver for sufficient time for subsequent printing processes.

Another main object is to employ this particular method of establishing a selection of elements to operate upon an electrical translator, including keyboard-transmitting, receiver-printing, and function-performing processes.

Another main object is to employ this particular method of establishing a selection of elements to operate upon a mechanical translator, including keyboard-transmitting, receiver-printing, and function-performing processes.

Other important objects will become apparent to those skilled in the art.

The principles of the invention are illustrated in the accompanying drawings, in which:

Fig. 1 is a schematic drawing showing the basic principles of the invention as applied to the electrical translator in a transmitting-receiving, printing-telegraph unit or station including a keyboard transmitter and a particular form of printer;

Fig. 2 shows the selecting mechanism in detail with transfer element coordinated with the timing reed, start-stop magnet and transmitting distributor as applied to set up a selection of electrical

elements for operation with the electrical translator.

Fig. 3 is an end view of the shuttle selector, selecting magnet, and transfer clutch cam and lever;

Fig. 4 is a view within the shuttle selector stator, showing the selector magnet armature with respect to the marking and spacing tracks internal to the stator frame;

10 Fig. 5 is an end view of the selector transfer;

Fig. 6 is a schematic diagram of the electrical components of the shuttle selector as applied to the electrical translator;

Fig. 7 is an end view of the electrical translator;

15 The above figures illustrate the principles of the invention involved in its application to an electrical translator and a continuously revolving type wheel printer.

The following figures illustrate the principles 20 involved in their application to the mechanical translator and the stop at print type wheel, introducing a number of new and novel interactive features and constituting a greatly improved printing telegraph machine;

25 Fig. 8 is a schematic drawing showing the basic principles of the invention as applied to the mechanical translator in a transmitting-receiving printing-telegraph unit or station, including a new and novel keyboard transmitter, and a particular form of printer designed specifically for the purpose;

30 Fig. 9 is an assembled front view of the shuttle selector coordinated with the reed escapement and distributors, the selector transfer operating directly into a Baudot five-slotted disc translator, 35 and including the stop at print type wheel, paper roller, driving motor, transmission, and related structural details. In this view the keyboard transmitter is removed, but certain cam elements 40 functioning in conjunction with the keyboard are shown at the extremity of the reed-escapement shaft;

45 Fig. 10 is an assembled view in side elevation of the shuttle selector in relationship with the selector transfer connected to the Baudot five-slotted disc translator, including the stop at print type wheel, paper roller and carriage, printing hammer mechanism, transmission, functional cam group, and keyboard transmitter with cam 50 release transmitting contact combination including keyboard lock and restore features. The details between the keyboard contact release cams and the shuttle selector; i. e., distributors, reed mechanism, etc., are removed in this figure; and

55 Fig. 11 is a side view of the transfer cam lever,

being also representative of other cam levers operating on the gang cam group.

We will first describe the various elements of the invention as applied to the electrical translator and continuously operating type wheel printer. Reference is made to Fig. 1, in which the intention is to represent one complete transmitting-receiving printing-telegraph station connected to an identical distant station (not shown) by line and ground connection. Obviously any complete circuit connection between the two stations, wire or radio, is within the scope of the invention. The elements shown within the dotted inclosure A constitute a conventional Baudot saw-toothed bar, five-unit code, keyboard transmitter with keyboard locking magnet and lock, which being well-known in the art require no detailed description here. The elements shown within the inclosure B represent the particular form of printer in this phase of the application, and are hereinafter described in detail. The details shown within the inclosure C represent schematically the resulting action through a Baudot electrical translator or combiner, the physical construction of which is shown by Fig. 7, and the detailed electrical connections and assignment as regards functions and characters are shown by Fig. 6. This particular arrangement is considered novel in that the marking-spacing combinations are in the ratio 2-2-4-8-16, which is a very economical arrangement, bearing in mind that the usual ratio is 2-4-8-16-32. However, it is believed the operation of such translators is generally understood and the description may be confined more particularly to the resulting action of the components shown within the inclosure C of Fig. 1.

The numeral 43 represents a high-speed line relay with armature 43 and local contact 46.

Having introduced the more or less conventional elements of Fig. 1, we will now describe the special devices acting upon these elements to produce very desirable results. Let it be assumed first that the gears 166, 134, 164 and 200 are driven in common from an electrical motor which is operating continuously.

The details which are shown mounted upon or above base 40 are shown in more detail in Fig. 2, and reference is now made to that figure. Gear 166 is not connected directly to shaft 165, but the shaft simply provides bearing for the gear. The gear drives one side of a friction or slip clutch 181, which in turn engages a driven side of the slip clutch 182 and 183. The detail 182 represents proper slip-clutch facing material. Member 183 carrying detail 182 is keyed to shaft 165, thus transmitting drive, and spring 184 provides the required degree of frictional clutch engagement. In brief, shaft 165 is driven by gear 166 through slip clutch 181, 182, 183, and will rotate accordingly when permitted to do so by the reed-operated escapement mechanism 172, 174, 175.

The reed-operated escapement mechanism is described in detail in our previous application, Serial #725,968, Patent No. 2,128,242, and hence but a brief description will be sufficient here. A reed 172 of given periodicity is clamped in position at mounting 179. At rest the reed is held in dotted position 172a. When permitted to vibrate by release of start-stop magnet armature 167, the reed operates through link 176, an escapement yoke 175 formed to present two pawls 175a and 175b, which escape the progressive movement of escapement pins 174a and 174b

shown, and 174c, 174d, 174e, and 174f not shown but located in staggered relationship equidistant about the periphery of escapement hub 174. The escapement hub 174 is keyed to shaft 165. Accordingly the reed 172 controls the progression of shaft 165, which rotates or tends to rotate through the friction drive of slip clutch 181, 182, 183 in six steps for each complete revolution of the shaft. The function of the electro-mechanical performance of the reed start-stop mechanism 62, 167, 171 is to release the reed, permitting the reed to vibrate three complete cycles (six half cycles; i. e., from 172a to 172b being one-half cycle and return from 172b to 172a being the other half cycle) after which the start-stop mechanism stops the reed in the initial position 172a. The shaft 165 is then at rest, with clutch slipping, except when permitted to rotate in definite steps by the reed-operated escapement.

Shaft 165 carries a transmitting distributor 49 and a start-stop functional distributor 57 as well as a cam-operated contact combination 41, 38, 39, which function in the keyboard-locking circuit. Proper bearings are provided for shaft 165 at 173 and 186.

The details to the right of bearing 186 on mounting 40, including selecting magnet 65 and details, constitute the shuttle selector and transfer element operating into the electrical storage receiver. These devices operating in combination with our reed-controlled escapement and subsequently described devices to constitute a complete transmitting-receiving printing-telegraph station, may be regarded as one of the major objects of our invention.

The shuttle selector comprises a two-track stator 189 mounted upon base 40; a rotor 190 to which are attached five shuttles, 190a, 190b, 190c, 190d, and 190e, the shuttles operating on one leg in either of tracks 189a or 189b; and a selecting magnet 65, the armature 66 of which determines the track taken by the individual shuttles during the rotation of the rotor 190. Cam 187 is a transfer function described later. An end view of the shuttle selector is shown in Fig. 3 and a plan view of a section of the stator 189 and of the selecting magnet armature 66 is shown in Fig. 4. Referring again to Fig. 2, each shuttle, 190a to 190e inclusive, is provided with another leg at right angles to the leg which operates in tracks 189a and 189b, and which we will term hereinafter as the transfer leg, as differentiated from the selecting leg. Whether the selecting leg is in track 189a (marking), or 189b (spacing), determines the position of the transfer leg, as for example shuttle 190c is shown in the spacing position, while the dotted lines show the marking position for this particular shuttle. The other shuttles act in an identical manner; i. e., the armature 66 of the selecting magnet 65 assigns each shuttle-selecting leg to either the marking track 189a, or the spacing track 189b, in one rotation of the rotor 190 from start to stop position, thus setting the shuttle transfer legs in marking or spacing positions as the case may be.

The selector transfer comprises a frame 192 which carries five marking-spacing cams, 192a, 192b, 192c, 192d, and 192e, in positions which coincide with the stop positions of the five shuttle transfer legs; a transfer shaft 197, which carries the frame 192, and which is shifted from the receive-selection position to the transfer-selection position by shift yoke 193, in engagement with drive pin 196; and a transfer-shaft bearing 195, which provides a key section operating in a key-

way on the shaft to prevent the shaft from turning. The selector transfer is shown in the receive-selection position in Fig. 2. With the frame 192 hub to the right against bearing 195 is the transfer-selection position. The movement is as indicated for the marking-spacing cams by the perpendicular dotted lines. Normally the position of the selector transfer is in the transfer-selection position to the right. After a selection has been established by the shuttle selector and is in stop position, the selector transfer operates to the position shown by properly timed cam action through lever 188 on shift yoke arm 193. The cam itself is a function of another shaft described later. It will be noted in the figure 15 that movement to the receive-selection position as shown, serves to present the arms of the cams 192a to 192e, inclusive, against the shuttle transfer legs 190a to 190e, inclusive, thus setting the cams in either marking or spacing position. The cams are so constructed as to remain in the position last set. Cam 192c is shown in the spacing position, the dotted radial line denoting the marking position. Upon the receipt of a given permuted selection from the shuttle selector, the 20 transfer then is returned by tension of spring 194, cam lever 188 permitting, to normal position with frame 192 hub against bearing 195, and as a result the marking-spacing cams 192a to 192e, inclusive, transfer their selection to the electrical 30 switches of the storage receiver or electrical selector.

A cross-sectional view of the physical construction of the electrical receiver is shown by Fig. 2, and the electrical relationship is shown by Figs. 1 and 6. A description of one switch combination will suffice for the five involved. In Fig. 2, contact lever 85 acts between contact springs 84 and 86 as a single-pole double-throw switch with marking-spacing positions. With transfer cam 192c in the spacing position shown, upon engaging the insulated tip member of contact lever 85, operates the lever in contact with spring 84 thus establishing a spacing connection. Operation of contact lever 85 to contact 86 constitutes a marking connection. The block 198, upon which all contact levers and springs are mounted, is of insulating material and, of course, proper insulation is provided between all current carrying members.

Referring again to Fig. 1, the details shown within the area inclosed by the dotted lines and designated D represent features which perform two primary functions; viz., to move the transfer frame, previously described, from normal or transfer selection position to receive selection position; and to establish electrical continuity through the selector receiver switches, the translator, and the printing magnet or function magnet as the case may be. Gear 134 is normally rotating under drive, as previously stated, hence shaft 135 and the driving side of the positive clutch 132 are also rotating. The driven side of this clutch 131 is held out of engagement by the rounded extension of arm 137, the lip on 131 being cam contoured to provide this condition. However, upon depression of arm 137 by the shuttle cam 187 the action about pivot 136 is to raise the extension of arm 137 out of restraint of clutch 131, thus permitting clutch engagement for one revolution only, whereupon 131 is returned to the position shown. Spring 133 provides the required clutch engage action. In this one revolution of clutch 131, shaft 130 is also rotated operating cam 129 upon cam lever 188 which serves to operate 75

the shift yoke arm 193 and selector transfer details of Fig. 2. Also shaft 130 drives the distributor arm 127 of the distributor 126, establishing continuity between wires 125 and 110 for the interval of segment 128 during the one revolution of the shaft. Necessarily the gearing, cams and distributor are properly timed with respect to each other and to other processes.

As stated above, the elements shown in the area 10 inclosed by the dotted lines and designated B, represent the particular form of page printer employed in this phase of the application. The printer comprises a continuously rotating type wheel 152 supported on carriage 153 and driven from shaft 156 by means of bevel gear 164; a printing hammer 154 and hammer pin 154a cam operated from an intermediate shaft which is engaged to the drive of shaft 156 at the proper time by magnet 150 and armature 158 action on positive clutch 157; a carriage-spacing mechanism which is gear driven on rack 155 the required distance each time clutch 157 is operated by the printing magnet 150; a carriage-return mechanism operating when rack 155 is disengaged from the step forward gearing by magnet 149 and armature 161, the return power being derived from spring 159 coiled in housing 160; a letters and figures shift consisting of magnets 147 and 148 which serve to raise or lower the paper roller 138 on shaft 141 in bearings 139 and 142 in guides 140 and 143; and a line-feed function consisting of magnet 146 acting through armature ratchet 144 on ratchet wheel 145 which serves to step shaft 141 and hence paper roller 138. Such features as paper guides and ribbon feed are not shown, being more or less conventional features, and in order not unduly to complicate the drawing.

Now it will be apparent that a definite timing of various shafts, cams, distributors, type wheel, and magnets is required throughout this transmitting-receiving printing telegraph mechanism. As examples in this respect the following relationship was used in the preliminary model and hence is pertinent to this description. The motor which drives gears 166, 134, 164, and 200 operates at 2100 R. P. M. Gear 164 and hence shaft 156 and type wheel 152 operate at 550 R. P. M. Gear 200 and the brush arm 201 of the translator also operate at 550 R. P. M. The printing hammer drive cam shaft and carriage space shaft on the driven side of clutch 157 operate at 2200 R. P. M. when the clutch engages under magnet 150 action. Gear 134 and resulting action operate at 412.8 R. P. M. Gear 166 operates at 431 R. P. M. but, and this is an interesting and vital feature, does not drive shaft 165 at this speed through the friction clutch 181, 182, 183 because the rotation of shaft 165 is determined by the frequency 60 of the reed escapement 174, 175. The clutch simply exerts turning moment to the shaft. The natural frequency of vibration of the reed 172 is 19.5 cycles per second acting in 3-cycle escapement on shaft 165, hence shaft 165 performs one 65 revolution in progressive steps at the rate of 390 R. P. M.

With further reference to Fig. 1, let us now consider a typical example of operation through all processes from the striking of a key at one 70 station to the resulting printing of the designated character, or the performance of a function at that same station and at the distant station. It is assumed that the circuits and equipment at the distant station are identical to that shown for the local station in Fig. 1. The gears 166,

134, 164 and 200 at both stations are revolving under motor drive. The line to the distant station is connected at L. A ground return is provided at 2 and battery at 3. The line circuit in normal state is from battery 3 by wire 4 to contact lever 22, contact 23, wire 11, wire 10, relay winding 48, wire 1 to distant station and through an identical circuit with distant battery aiding to ground, return by 2 to battery 3. Transmitter bars 25, 26, 27, 28 and 29 and universal bar 24 are to the right as shown with contacts 17, 18, 19, 20 and 21 open. The keyboard locking magnet is de-energized because the circuit, battery 3, magnet 33, wire 37, cam lever 38, cam contact 39, wire 36, return to battery 3, is open at contact 39. Line relay 48 is energized because, as described above, the line circuit is closed and hence armature 43 is closed with respect to contact 46 setting up a parallel circuit of two branches, one of which holds energized start-stop magnet 62 and the other holds energized the selector magnet 65. The respective circuits are, battery 3, wire 4, wire 63, start-stop magnet 62, wire 61 to distributor 57, distributor arm 58, segment 60, wire 45, contact 46, armature 43, wire 42, wire 39 return to battery 3; and battery 3, wire 4, wire 64, selector magnet 65, wire 47, contact 46, armature 43, wire 42, wire 36 return to battery 3. The fact that the start-stop magnet is energized and armature 167 held down results in the reed 172 being held at rest in position 172a under latch 171, which in turn means that escapement pawl 175a is restraining hub 174 from movement at pin 174a and hence shaft 165 is at rest with clutch 181, 182, 183 slipping although gear 166 is revolving. Distributors 49 and 57 and cam wheel 41 as well as the shuttle selector are at rest in normal state. The fact that the selector magnet is energized at this time has no particular significance other than circuit simplification.

The selector transfer 192, is in its normal position, which is that of transfer selection (to the right in Fig. 2) with the last received selection of marking-spacing permutations set up in the switches 79 to 91 inclusive (that selection not shown). This circumstance is of no moment at this time.

The translator C is running; i. e., the brush arm 201 is sweeping the segments, but this also is incidental because the selector-translator-printer circuit is open at distributor 126. The distributor 126 is at rest with brush arm 127 on an inactive insulated segment. Shaft 130 and cam wheel 129 are at rest due to clutch 131, 132, 55 being disengaged, although drive side 132 is revolving. The printer B is at rest.

Having described the normal or at rest condition, let us assume key 32 is depressed by the operator. Transmitter bars 26, 28 and 29 are moved to the left or marking position thus closing contact levers 13, 15 and 16 with contacts 18, 20 and 21 respectively; and bars 25 and 27 remain to the right as shown in spacing position leaving contact levers 12 and 14 open with respect to contacts 17 and 19. This permutative arrangement corresponds to the letter G in the Baudot code. The universal bar is also at the same time moved to the left opening contact lever 22 with respect to contact 23, thus opening the 70 line circuit at that point.

The opening of the line circuit releases line relay 48 at the local station and at the distant station. Armature 43 releases, thus deenergizing the start-stop magnet 62 and the selector magnet 75

55 at both stations. Accordingly, reed 172 is released by armature 167 and, by moving from position 172a to 172b, permits shaft 165 to rotate from pin position 174a to the position of engagement of pin 174b on escapement pawl 175b. The subsequent escapement actions are described fully in our application, Serial No. 725,968, Patent No. 2,128,242. However, having been released shaft 165 will be permitted to rotate in six successive equidistant steps to stop position with armature 167 down, reed 172 stopped in position 172a, and pin 174a engaged on escapement pawl 175a. In the first half cycle of reed action the shaft 165, having rotated one-sixth revolution, positions distributor arm 50 on segment 51; distributor arm 58 on segment 59; cam wheel 41 lift action on cam lever 38 to contact 39; and presents the shuttle selector leg 190a (Fig. 3) to the selector magnet armature 66 (Figs. 3 and 4). The distributor arm 50 has now connected line wire 10 to transmitter contact 17, which being open with respect to lever 12, constitutes a spacing interval. The movement of distributor arm 58 to segment 59 simply had the effect of removing the windings of start-stop magnet 62 from connection to the line relay contact 46, segment 59 being entirely insulated and disconnected from all circuits. As will be seen later, when distributor arm 58 reaches segment 60a, the start-stop magnet will be energized in anticipation of the return of reed 172 to position 172a under latch 171 on the sixth half cycle, and in order to give the magnet ample time for operation. The closure of cam lever 38 and contact 39 has energized the keyboard locking magnet 33 and hence locked up the keyboard by means of armature bar 35. The shuttle selector magnet 65 is de-energized at this particular time, due to the line circuit being open at contact 17 (spacing position), and line relay 48 contact 46 being open in spacing position also, with the result that the shuttle selector leg 190a is directed into the spacing track 189b of stator 189 by the selector magnet armature 66. These same actions occur at the distant station, with the exception that at that station the keyboard transmitter has not been actuated and is in the normal condition shown in Fig. 1, with distributor 49 and the keyboard-transmitting contacts 17 to 21 inclusive shorted out of the line circuit by wire 11, universal bar contact 23, and lever 22.

50 The reed escapement now permits shaft 165 to rotate to the next pin position placing distributor arm 50 on segment 52. This is a marking segment at this time because the keyboard transmitter lever 13 is against contact 18 (our initial assumption for letter G, 2, 4, 5, Baudot code), and hence current from battery 3 flows through the line circuit energizing local and distant line relays 48 and moving their armatures 43 to marking position with respect to contact 46, thus energizing selector magnet 65 which moves armature 66 to marking position. The shuttle selecting leg 190b (Fig. 3) is now presented to armature 66 (Fig. 4), which directs the selecting leg into marking track 189a.

55 The process is repeated for three more half cycles of the reed escapement, permitting shaft 165 to progress distributor arm 50 to segments 53, 54, and 55 in turn. Segment 53 at this time is a spacing segment, and segments 54 and 55 are marking segments due to the arrangement of the contacts and levers of the keyboard transmitter. The shuttle-selecting legs 190c, 190d and 190e are routed consecutively by the selecting magnet 65 into marking-spacing tracks of stator 189 as

follows: 190c into track 189b spacing, 190d into track 189a marking, and 190e into track 189a marking. All five shuttle selectors have now been assigned to a marking or spacing position. During the fifth half cycle of the reed escapement, distributor arm 58 contacts segment 60a of distributor 57 causing magnet 62 to draw down armature 167. The reed 172 at this instant is moving from position 172a to 172b. Hence latch 171 is now down, awaiting the return of the reed on the sixth and last half cycle, and upon the reed passing in under the latch the reed will be restrained from further movement.

In the sixth and last half cycle of the reed to stop position, shaft 165 rotates to the initial stop pin 174a. Distributor arm 50 stops on segment 56; distributor arm 58 stops on segment 60; cam wheel 41 releases cam lever 38 from contact 39; universal bar 24 is released by magnet 33 to return to normal, closing contact 23 and lever 22; cam 187 operates cam lever 137 and shaft 165 positions the shuttle selector in the initial position shown in Fig. 3. All members of shaft 165 have returned to normal, the keyboard transmitter is normal and a selection has been set up in the shuttle selector.

We will now see how this selection is transferred to operate through the electrical selector and translator upon the printer. When cam lever 137 was operated, clutch 131 was permitted to engage clutch 132, causing shaft 130 to rotate cam 129. Cam 129 depresses the cam lever 188, which in turn operates the transfer shift yoke lever 193, shown in Fig. 2, to advance the transfer shaft 197 and frame 192 to the receive-selection position with marking-spacing cam arms 192a to 192e, inclusive, thrust against the set selection of the shuttle transfer legs 190a to 190e inclusive. This action causes each marking-spacing cam 192a, 192b, 192c, 192d, and 192e to take either a marking or a spacing position as dictated by the positions of the individual shuttle transfer legs 190a 190b, 190c, 190d and 190e. Hence cam 192a is set in spacing position, cam 192b in marking position, cam 192c in spacing position, and cams 192d and 192e in marking positions. Further movement of shaft 130 returns the entire transfer assembly to transfer position, and transfers this selection to the electrical switches 79, 82, 85, 88 and 91. Now it will be recalled that the translator C is operating continuously; i. e., the brush arm 201 continues to sweep over the segments shown in detail in Figs. 6 and 7. In other words the function of the translator is to seek out a continuity path matching the selection set up in the electrical selector. At the instant this continuity of path is found, pertinent printer action occurs as described below.

With further reference to Fig. 1, the switches of the electrical selector are shown in the position set by the shuttle-selector transfer. Also the translator C is shown diagrammatically in the position where continuity is afforded which in our assumption is the letter G. Needless to say the G position of the type wheel of the printer is timed accordingly by proper gearing considerations. Also shaft 130 having cam operated the transfer in further movement connects distributor arm 127 to segment 128 of distributor 126, thus closing the circuit from battery through selector, translator and printing magnet for the proper duration of time. This circuit is as follows: battery 3, wire 125, distributor arm 127, segment 128, wire 110, selector lever 79 (spacing), contact 78, wire 68, segments 93 (spacing), brush

94, strap 111, brush 97, segments 98 (marking), wire 71, contact 83, selector lever 82 (marking), wire 108, selector lever 85 (spacing), contact 84, wire 72, segments 99 (spacing), brush 100, strap 112, brush 103, segments 104 (marking), wire 75, contact 89, selector lever 88 (marking), wire 109, selector lever 91 (marking), contact 92, wire 71, segment 107 (marking), brush 106, strap 113, brush 119, character segments 118, wire 124, windings of print magnet 150, return to battery 3 by common wire 151. The print magnet armature 158 connects positive clutch 157 to drive shaft 156. A proper cam related to the driven side of the positive clutch 157 delivers the thrust to hammer 154 which strikes pin 154a. The pin thrusts the type character G against the paper carried on roller 138, it being understood that a proper typewriter ribbon is interposed between the type and paper. From the foregoing it will be apparent how any other character or printer function is selected and performed.

We have now shown how we maintain exact synchronization between the processes of transmission and reception, and in addition how we permutatively set up a selection and transfer that selection subsequently to an electrical translator acting on printing processes.

Having described sufficiently the first phase of our invention; i. e., the application to the electrical translator and the continuously revolving type wheel printer, and having established in the reader's mind the required background, we will describe hereinafter the application of the principles involved to the mechanical translator and the stop-at-print type wheel, constituting in effect a new, novel, and complete printing telegraph mechanism or station, as will be appreciated by those initiated in the art.

Reference is now made to Figs. 8, 9, 10, and 11. Fig. 8 is a schematic drawing showing the principles involved and the theory of operation, while on the other hand Figs. 9, 10, and 11 are actual construction drawings, showing the various parts in detail and the location and relationship thereof. The same reference numerals are used throughout all drawings wherever practicable and therefore, while the following description will mainly concern Fig. 8, it is to be understood that when any doubt arises in the reader's mind reference to Figs. 9, 10, and 11 is intended, whether or not so stated. It is believed that too frequent mention of cross references may be confusing rather than helpful.

In Fig. 8 the intention is to represent one complete transmitting-receiving printing-telegraph station or unit connected to an identical distant station or unit (not shown) by line and ground connection. Any complete electrical circuit connection between the two stations, wire or radio, is within the scope of the invention. The Baudot five slotted disc translator employed is shown in housing 213, the discs being 215 and the stunt bars 214. The principle of operation of such translators is well known to those versed in printing telegraph practice. Suffice it to say that each of the five discs 215 are slotted in such relationship that a given permuted arrangement of the five discs with respect to each other will permit only one stunt bar to fall outward in a coincidence of slots. This circumstance is arranged to effect the stoppage of the type wheel unit 152 at any one of 32 radial positions, there being 32 possibilities in the five-unit code. The type wheel having stopped in the selected position, certain printing, carriage step forward, ribbon feed, etc.,

functions occur as will be described in detail hereinafter. Our purpose is to show how we operate upon these elements to effect our desired result in the following sequence; keyboard operation setting up a permuted arrangement of transmitting contacts and releasing the reed escapement mechanism; reed escapement progression of the selection processes; transference of selection to the translator with subsequent functional performance.

The mechanical transmission features; i. e., from driving motor to various shafts, clutches, etc., should be understood first. The driving motor is 223 which we will assume to be operating continuously. The motor drive is connected to shaft 135 through gears 224 and 134. It will be noted that a gang cam group is mounted on sleeve 130 on this shaft 135 and the sleeve 130 is normally held out of drive by disengagement of positive clutch member 131. In order not to break the continuity of thought, we will return to the description of this cam group later. Shaft 135 transmits continuous drive through gears 225, 226, 227, and 166 to the vertical shaft 211. Accordingly it will be seen that the vertical shaft 211 is in continuous rotation in the direction indicated by the arrow. Now the vertical shaft 211 is equipped with two friction or slip clutches, one providing driving torque for the rotor 190 of the shuttle selector, and the other providing driving torque for the type wheel 152. The rotor 190 of the shuttle selector is equipped, at the upper section, with a frame carrying externally the five shuttles (a similar arrangement to that shown in Fig. 3) and internally the friction clutch 181, 182, 183, and 184, while the lower tubular section is equipped with a bevel gear in engagement with the bevel gear 228. (In Fig. 9 details 183 are the driven clutch members attached to the rotor 190; 181 is the driving member attached to the shaft 211; details 182 are proper slip clutch material and the spring providing frictional engagement is 184.) The bevel gear 228 is keyed to the reed escapement shaft 165, which is equipped with the escapement hub 174 in proper relationship to the reed-driven escapement 175. These features are fully described in the first phase of this invention as well as in our application Serial No. 725,968. The reed is shown at 172 and the reed start-stop magnet at 62. The reed escapement shaft 165 is equipped with the start-stop functional distributor 57, and also the transmitting distributor 49 as previously described. The cams 243 and 244, carried on the end of the reed escapement shaft 165, perform keyboard functions to be described later. The feature to be emphasized at this point is that the vertical shaft 211 is rotating continuously, and tending to rotate the shuttle selector rotor 190 and the reed escapement shaft 165, through torque at the friction clutch 181, 182, 183 and 184; but that the progression of the shuttle selector rotor 190, and the reed escapement shaft 165, is determined by the performance of the reed controlled escapement 175. In other words, shaft 211 provides the drive, but the progression of shaft 165 and rotor 190 is a function of the reed performance.

As stated above, shaft 211 is provided with another slip clutch for the type wheel 152. The type wheel is so constructed as to present type bars externally in radial disposition as shown, and is equipped internally with the friction clutch affording slip engagement with the vertical shaft 211. (In Fig. 9 the type wheel driven

members are 233, the shaft drive member 206, proper clutch material 207, and clutch tension spring 209.) It will be apparent that the type wheel is rotated or stopped, dependent upon the action of the translator stunt bars 214 upon the stop member 212 attached to the type wheel.

Returning to the gang cam group mounted on sleeve 130, as stated above, this combination is normally motionless because positive clutch member 131 is held out of engagement by lever 137. However, when shaft 165 performs one revolution, lever 137, pivoted at 136, is disengaged by cam 187 permitting clutch engagement of 131 with 132; hence the gang cam group performs one revolution and is then disengaged by lever 137. These cams perform functional features as follows: 231 operates the ribbon feed; 129 operates the shuttle selector transfer shift arm 193 through cam lever 188; 230 operates the print hammer 154 (Fig. 10) through cam lever 232 on the down stroke and the carriage step forward ratchet arm 237, through member 234 on the up stroke; 229 performs the functions (not shown) of carriage return, line feed, and figures and letters shift, through trigger action of pertinent translator stunt bars 214 upon connecting links. These latter features are not shown because it is not desired to unduly complicate the figures.

Let us return now to the description of this application of the shuttle selector, transfer, and the direct action of transference of selection to the translator. The rotor of the shuttle selector is 190 equipped with the five shuttles 190a to 190e, inclusive, which have selecting legs operating in stator track 189a marking or 189b spacing, the theory having been previously described in connection with Fig. 4; i. e., the selecting magnet armature 66 at a given instant upon rotation of the rotor 190 assigns each of the five selecting legs 190a to 190e inclusive to either the marking track 189a or the spacing track 189b dependent upon whether armature 66 is in marking or spacing position. The shuttle selector stator 189 is supported by frames 219 and 220 (Fig. 9), which also serve to support the translator housing 213. The shuttles 190a to 190e, inclusive, also have the transfer legs at right angles to the selecting legs, the transfer legs being positioned to act upon the transfer cams 192a to 192e, inclusive. (These members are called cams because they are so termed in the description of the first phase of this invention and an effort has been made to preserve the same nomenclature and detail numbers throughout insofar as practicable.) The selector transfer, however, in this phase of the invention performs two functions; i. e., to transfer the selection from the shuttle selector to the five translator discs 215 by direct mechanical action, and to reset the translator stunt bars 214. The selector transfer frame is 192, with the transfer cams 192a to 192e, inclusive, pivoted about the lower section, the transfer shift yoke 193 engaging directly above, and at the upper section is provided with a reset disc so formed as to reset any of the stunt bars 214 upon downward movement of the selector transfer frame. This feature will be appreciated upon an examination of the relationship shown in Fig. 9. Also, upon downward movement of the selector transfer, the cams receive the selection from the shuttle transfer legs and hence assume marking or spacing positions. Let us examine the action of these cams 192a to 192e upon the five translator push-pull bars 216a to 216e, inclusive. In marking position the cams

force the push-pull bars out, and in spacing position draw these bars in. The pin engagement of the cams into slots in the bars in conjunction with the V section in the housing above each cam afford this action upon operation of the transfer frame. This action will also be appreciated upon an examination of Fig. 9. Now the push-pull bars 216a to 216e inclusive in marking or spacing positions, set the pertinent translator slotted discs 215 in marking or spacing positions by means of the individual shafts 217a to 217e arranged about the translator housing 213.

The keyboard transmitter is shown schematically in the lower right hand section of Fig. 8 and in actual construction in the lower left-hand section of Fig. 10. This keyboard transmitter is new and novel in numerous respects and provides certain advantages over types developed to date. These advantages will become apparent to those skilled in the art as the description is continued, and are briefly as follows: equal throw for all keys; the elimination of thrust action of key bars upon saw-toothed lateral members, the lateral members being pivoted at their extremities resulting in a reduction of frictional effects; the provision of means for the assembly of code combinations on any key without the limitations of being restricted to a given permuted arrangement of fixed saw-teeth on a number of bars; and the inclusion of a uniform load cam combination directly on the reed-controlled shaft, which releases and restores the keyboard contact lever combinations as well as operates in conjunction with keyboard lock members. Referring again to Fig. 8, one key is shown at 32. The code bars common to all keys and pivoted each at two extremities on the same axis are 25, 26, 27, 28, and 29. It will be noted that the permuted arrangement for each key with respect to the common code bars is accomplished by the disposition of identical extension fingers in marking or spacing positions. Projection of the fingers to the right of the key is marking position and to the left of the key is spacing position. The universal bar 24 is acted upon by all keys. Upon depression of a given key (the key 32 in Figs. 8 and 10 is shown depressed) the extension code fingers of that key rock the code bars 25, 26, 27, 28 and 29 into marking or spacing positions. The code bars in turn operate upon contact pawls 267, 268, 269, 270 and 271 which are pivoted on a common center line between the code bars and the code transmitting contact levers 12, 13, 14, 15 and 16. In stop or restore position the transmitting contact levers are held away from contacts 17, 18, 19, 20 and 21 by the release bar 256 which is pivoted at 257 and 258, but in this position the bar permits closure between an additional contact combination; i. e., contact lever 22 and contact 23 which may be termed start-stop contact members. The contact levers are insulated from the release bar. In Fig. 8 the release bar is shown in the release position, its normal position being as indicated to the right by the dotted line. Now it will be seen that with the release bar in normal position and all transmitting contact levers held away from their respective contacts, and the start-stop contact combination closed, the contact pawls 267, 268, 269, 270 and 271 are free to receive a marking or spacing setting from the code bars. Upon being set in the desired position by key operation, simultaneous operation of the universal bar latch 260 permits

the release bar 256 to move away from the contact levers in turn, permitting the contact levers to make their respective contacts under the residual spring tension set in the contact levers, if the contact pawls do not interfere (marking position), and at the same time removes the start-stop contact lever 22 from contact 23. The contact pawls do interfere, if in spacing position, and prevent the pertinent contact levers from closing with the contacts. Attention is invited to the fact that the release bar locks the contact pawls in position by the interposition of teeth on the release bar with respect to pins on the contact pawls (see Fig. 10) and hence locks up the keyboard.

The universal bar latch 260 is so arranged, that upon the depression of a key the latch is removed from behind the extension 259 of the release bar, thus permitting the release bar to move to the left under the action of its retractile spring. Also the trip pawl 262, attached to the universal bar 24 which lifted the latch 260 from engagement with the extension 259 is in turn disengaged from lift action on latch 260 by being cammed out of engagement by roller 263. The latch is accordingly free to fall in place behind extension 259 upon the release bar returning to normal. The reason for this feature is to prevent repetitive operation upon holding down a key. As arranged, a key must be depressed for each and every operation.

We have discussed the release features of the bar 256. Let us now describe the restore features of this bar, through the agency of the cam combination on the reed escapement shaft, which results in removing the lock from the keyboard, opening all transmitting contacts, and restoring the start-stop contact lever 22 to close with contact 23. Before doing so, however, let us first invite attention to the pin 254 in the slot of link 253 and to the fact that this pin does not prevent bar 256 from releasing and moving from the right or restore position to the left or release position upon disengagement of the keyboard latch 260. This pin performs a restore function, but does not prevent the release function. To continue, two cam discs 243 and 244 are mounted on the reed escapement shaft 165. Roller 252 operates on cam disc 243 and roller 251 operates on cam disc 244. The relative positions in which these items are shown is that of start which of course coincides with that of stop. The roller 252 on cam disc 243 in conjunction with arm 245 and link 253 actually delivers the restore stroke to the bar 256 through pin 254; but throughout one revolution of shaft 165, cam disc 244 and roller 251 have been building up tension in spring 249 through arm 250 for the purpose. A careful examination of the cam disc formations will make this clear. The link 246, between arms 245 and 250, performs no function other than preventing the two arms from approaching any closer together than shown in the figures, but permits arm 250 to move away from arm 245 as it builds up spring tension in the performance of a revolution by cam disc 244. As roller 252 falls into the stop recess of cam disc 243, spring 249 delivers the restore stroke to bar 256 through arm 245, link 253 and pin 254, which is followed immediately thereafter by fall off of roller 251 on cam disc 244, resulting in a setting as shown in the figures but with the bar 256 in the restored position to the right rather than in the released position to the left. The bar 256 is shown in

the released position for descriptive reasons to be used later on the assumption that a key has just been depressed. Obviously arms 245 and 250 are pivoted at 247 and 248.

Several miscellaneous items appearing in the figures have not been mentioned up to this point and these should be described before proceeding further. In Fig. 8, the numeral 48 designates a high-speed-line relay with armature 43 and contact 46. In Fig. 10, the numeral 210 designates an arm which restores any given type bar which has completed printing; 154a is the hammer pin operating upon the presented type bar; 154 is the printing hammer; 241 is a paper tube for storing rolls of paper, should such be desired, although often paper will be used as in the regular typewriter; the carriage is pivoted at 240 to permit of shifting to the letters or figures position with the step forward rack at 238 and the carriage return spring housing 160; and 221 is the rack which supports the operating lever arms coordinated with the cam group mounted on sleeve 130, the bearing center of the levers being shown at 222 in Fig. 9. One of these levers is shown in detail in Fig. 11. As mentioned previously, certain additional functional features are mentioned in this description which are not shown in the drawings due to the desire not unduly to complicate the drawings, but the interaction of the devices shown upon these functional features will be appreciated by those skilled in the art. As examples in this respect, it has been shown how the translator stunt bars 214 effect stoppage of the type wheel in character printing positions, but four of these stunt bars stop the type wheel in blank positions, the movement of the stunt bars being used to operate trigger link members presenting function performing members to the action of cam 229. The functions in question are line feed, carriage return, figures shift and letters shift. Also the ribbon feed is driven from cam 231 in such a manner that every revolution of the cam serves to ratchet the ribbon progressively through a pinion gear transmission, this drive being automatically reversible.

With further reference to Fig. 8, let us now consider a typical example of operation through all processes from the striking of a key at one station to the resulting printing of the designated character, or the performance of a given function at that station and at the distant station. It is assumed that the circuits and equipment at the distant station are identical to those shown for the local station in Fig. 8. The two stations are connected together by line wire continuation at L and earth return at 2. Obviously any electrical connection between the two stations is within the scope of the invention. Let us first describe the normal state of the various elements before a key is depressed. The motor 223 is operating continuously at both stations, and hence shafts 135 and 211 are in continuous rotation, but the gang cam group on sleeve 130 is at rest held out of drive at clutch 131. All keys are up, latch 260 is behind extension 259, the release bar 256 is to the right in restore position with contact levers 12, 13, 14, 15, and 16 away from contacts 17, 18, 19, 20, and 21, and with contact lever 22 closed with respect to contact 23. The distributor arm 58 is as shown with the brush contacting segment 60 of the distributor 57, and the distributor arm 50 is also as shown with the brush contacting segment 56 of the distributor 49. The start-stop cam com-

bination 243, 244, 251 and 252 is as shown. The reed 172 is in position 172a held by armature latch 171 of magnet 62. Escapement pawl 175a is opposing movement of pin 174a and hence shaft 165 and the shuttle selector rotor 190 are at rest with friction clutch 181 slipping. The shuttle selector transfer 192 is in the position shown in the figure, with the marking-spacing cams 192a to 192e in the positions of the last received selection, the push-pull bars 216a to 216e, inclusive, and the translator bars 215 being similarly disposed. The type wheel is stopped at the last selected stunt bar 214 with friction clutch 206 slipping. All functions are in normal position.

The line circuit is, starting with battery 3, wire 4 to contact 23, contact lever 22, wire 11, wire 10, line relay 48, wire 1, and by line wire to the distant station, whereby a similar circuit connection is made through battery aiding to ground and return to battery 3 at ground 2. The selector circuit is, battery 3, wire 4, wire 64, magnet 65, wire 47, line relay contact 46, armature 43, and wire 42 return to battery 3. The selecting magnet 65 being energized, armature 66 is in marking position. The reed start-stop circuit is, battery 3, wire 4, wire 63, start-stop magnet 62, wire 61, distributor arm 58, segment 60, wire 45, line relay contact 46, armature 43, and wire 42 return to battery 3. The start-stop magnet is energized holding reed 172 in position 172a by armature latch 171.

We will assume that key 32 represents the letter G and is coded 2, 4, 5, marking, and 1, 3, spacing, in the Baudot five-unit code, and that this key is now depressed as shown in Fig. 8. The universal bar 24 is operated and code bars 26, 28 and 29, and contact pawls 268, 270 and 271 are set in marking positions, while code bars 25 and 27 and contact pawls 267 and 269 are set in spacing positions. The release bar is released by latch 260 and moves to the left. Trip 262 is cammed out from under latch 260 by roller 263. Contact lever 22 is lifted off contact 23, contact lever 12 is not permitted to close with contact 17 because pawl 267 in spacing position is interposed, contact lever 13 is closed with contact 18 pawl 268 being in marking position, contact lever 14 is not permitted to close with contact 19 because pawl 269 in spacing position is interposed, and contact levers 15 and 16 are closed with contacts 20 and 21, respectively, pawls 270 and 271 being in marking positions. In brief, the line circuit has been opened at contact lever 22 and the code for the letter G has been set up in the transmitting contacts.

At the distant station no key having been depressed, that station being for the time the receiving station, the keyboard contact combination remains in normal position and preserves the continuity of line circuit at contact lever 22 throughout the subsequent operations.

The line circuit having been opened at contact lever 22 at the local transmitting station, the line relay 48 is de-energized at both stations, and from now on the performance being the same at both stations, except for keyboard contact restoration, the description will be confined to the local station with the understanding that the performance is duplicated at the distant station. The line relay armature 43 falls away from contact 46, de-energizing the selector magnet 65, which releases armature 66 to move to spacing position, and also de-energizes the reed start-stop magnet 62 and hence releases the reed 172

which moves from position 172a to position 172b on the first half cycle. The reed driven escapement pawl 175a also moves to the left from under pin 174a, thereby permitting shaft 165 to rotate until pin 174b is stopped by pawl 175b. Distributor arm 50 of the transmitting distributor 49 moves to segment 51, and contact lever 12 being in spacing position, the line relay 48 remains de-energized and armature 43 being open with respect to contact 46, the selecting magnet 65 also remains de-energized with the selecting armature 66 in spacing position. In the progression of shaft 165 from pin position 174a to 174b, the shuttle selector rotor 190 has also progressed to a corresponding angular position and in so doing has presented the selecting leg of shuttle 190a to be routed into the spacing track 189b by the armature 66 then in spacing position. The distributor arm 58 of distributor 57 has likewise moved from segment 60 to segment 59 which is insulated from the rest of the circuit, the purpose being to remove the reed start-stop magnet from the circuit throughout segment 59 in order that this magnet will be inactive during that period. The reed 172 now returns from position 172b to position 172a and releases pin 174b at escapement pawl 175b, thus permitting shaft 165 to rotate to the next pin position; i. e., pin 174c which is stopped by escapement pawl 175a. Distributor arm 50 of the transmitting distributor 49 moves from segment 51 to segment 52, and contact lever 13 being in marking position, the line relay 48 is energized through the circuit, battery 3, wire 4, contact lever 13, contact 18, wire 6, segment 52, distributor arm 50, wire 10, relay 48, wire 1, and by line wire through distant circuit of wire 1, line relay 48, wire 10, wire 11, contact 22, contact lever 23 closed, wire 4, battery 3 aiding and return to local battery 3 at ground 2. The energized line relay 48 attracts armature 43 to contact 46, and hence energizes the selector magnet 65 which places the selector magnet armature 66 in marking position, thereby directing the selecting leg of shuttle 190b into marking track 189a, it being understood that the shuttle selector rotor 190 progresses with shaft 165. In fact the angular movements of progression of distributor rotors 50 and 58 and the shuttle selector rotor are identical.

The process as described above is repeated for three half cycles of the reed in which the distributor arm 50 is permitted to rotate consecutively from segment 52 to 53, 53 to 54, and 54 to 55, in phase with distributor arm 58 and with the shuttle selector rotor 190, thereby assigning the selecting leg of shuttle 190c to spacing track 189b, of shuttle 190d to marking track 189a, and of shuttle 190e to marking track 189a, as determined by the position of contact levers 14, 15 and 16 with respect to contacts 19, 20, and 21 and the subsequent performance of the line relay 48 and the selecting magnet 65 in spacing and marking positions. Upon the arrival of distributor arm 58 on segment 60a of distributor 57, it will be noted that the start-stop magnet 62 is then connected to battery, causing operation of armature 167 in anticipation of the return of reed 172 under latch 171. The sixth or last half cycle of the reed now occurs; i. e., the reed moves from position 172b to initial position 172a and in so doing is locked in that position by latch 171. Shaft 165 rotates from escapement pin 174f to escapement pin 174a which is the initial or stop position and is held there by escapement pawl 175a. In this progression of shaft 165, the cam

group 243 and 244 come into action, causing arm 250 to pull upon arm 245 through tension of spring 249, that tension having been built up throughout the revolution of cam 244 on roller 251, and when roller 252 drops into the start-stop depression of cam 243, this spring tension is exerted to restore bar 256 through link 253. The keyboard and transmitter are now returned to normal, with all transmitting contact levers open with respect to the contacts, and with the start-stop contact lever 22 closed with respect to contact 23; with latch 260 engaged behind extension 259; and with key 32 restored under action of spring 266. The line circuit is now closed as at the start of our operational example. In the progression of shaft 165 from the fifth to the sixth position, rotor 50 of the distributor 49 moves from segment 55 to the initial insulated segment 56, and rotor 58 of distributor 57 moves from segment 60a to segment 60, thereby restoring the connection 61 of the start-stop magnet 62 to operation from the line relay 48 armature and contact combination 43 and 46. Shaft 165 in this same progression presents cam 187 to operate clutch arm 137 after which, as stated above, shaft 165 stops at escapement pin position 174a. Now the shuttle selector rotor 190 being the driving member for shaft 165 has performed the same angular progression and is also stopped by virtue of the gear connection with shaft 165. The position in which the shuttle selector rotor stops coincides with its starting position, and all shuttles have been set in the marking-spacing code for letter G, with their transfer legs presented for the subsequent action of the selector transfer 192.

When the cam 187 operated clutch arm 137, the positive driven clutch member 131 was permitted to engage the driving clutch member 132 under action of spring 133. As characteristic of the action of the particular type of clutch and arm shown, one revolution of the clutch member 131 again disengages that member by means of the cam contoured surface acting on the rounded extremity of arm 137. However, in that revolution clutch member 131 drives the sleeve 130 of the gang cam group mounted thereon. These cams are contoured to perform their various functions in a definite sequence.

Cam 129 is the first to operate upon cam lever 188, which in turn operates the transfer shift yoke arm 193 about pivot 191. The cam thrusts roller and cam lever 188 up (normally held down and restored by spring 194, Figs. 10 and 11), hence thrusting arm 193 up and, being pivoted at 191, the yoke engaging the transfer frame 192 down. This action presents the marking-spacing cams 192a to 192e, inclusive, to the shuttle transfer legs 190a to 190e, inclusive, which latter having been set 190b, 190d, and 190e marking and 190a and 190c spacing, transfer that selection to the transfer marking-spacing cams as 192b, 192d, and 192e marking, and 192a and 192c spacing. As the transfer frame 192 moved down, the reset disc at the top of the frame restores the translator bar 214 (previously selected) to the no-selection position, hence all bars are aligned receptive to a selection. Upon cam 129 now permitting cam lever 188 to move down under action of spring 194, the transfer frame 192 is moved up; i. e., returned to normal, and in so doing the marking-spacing cams 192a to 192e, inclusive, operate upon the push-pull bars 216a to 216e, inclusive, setting those bars in the positions 216b, 216d, and 216e marking, and 216a and 216c

spacing. These push-pull bars in turn by rotation of shaft 217a to 217e, inclusive, set the five individual translator slotted discs 215 in the relationship 2, 4, 5, marking and 1 and 3 spacing. Properly timed thereto by the upward motion of the reset disc of the transfer frame 192, one of the stunt bars 214 falls into the coincidence of slots of the translator slotted discs, being drawn therein by an individual spring, and being in the assumption of our operational example, a 10 stunt bar falling in the location designed to stop the type wheel 152 in the position with the letter G facing the paper, and with that type bar extension under the hammer drive pin, and also with that type bar in line with the printing slot. Obviously the type wheel 152 has rotated under the friction drive of clutch 206 from the time of stunt bar reset to stunt bar select which in a properly timed arrangement need never exceed one revolution of the type wheel.

Referring to Fig. 10, the type wheel character G is now properly positioned with respect to the printing slot in the frame plate and also properly positioned with respect to the hammer drive pin 154a. The hammer 154 is now pulled down sharply by action of cam lever 232 and spring 233 upon properly timed fall off of cam 230, the hammer blow being transmitted through the hammer drive pin 154a to sharply rotate the type bar of the letter G against the paper on roller 138, 30 whereupon the hammer is restored by cam action, the hammer pin by spring action, and the type bar by spring action on member 210. The return motion of hammer 154 serves to carriage step forward through arm 234, acting on ratchet 35 237 engaging rack 238.

Returning to Fig. 8, the gang cam group during its rotation, and previously to the printing hammer actuation, operated cam 231 performing the ribbon feed function, and presented cam 229 40 potentially active to deliver the power for such functions as carriage return, line feed, figure shift, or letter shift, had one of those functions been selected instead of, as in our assumption, the letter G.

As regards the rate of rotation of the vacuum shafts and other rotational elements with respect to the vibrating reed, the following relationship has been found to be very satisfactory; reed 21 cycles per second which escapes shaft 165, and the shuttle selector rotor 190 at the rate of 420 R. P. M.; motor drive and hence rotation of shaft 125, 450 R. P. M.; and vertical drive shaft 211, 600 R. P. M.

We have shown the advantages of our method of selection and transfer selection under the progressive steps established by the reed driven escapement. It is believed that the consistency of these processes will be apparent to those skilled in the art. In addition, we have shown an entire interactive complete printing telegraph unit in Figs. 8, 9, 10 and 11 and the related description, which has many advantages other than those previously cited. The simplicity of design and compactness should immediately become apparent. In fact, the model machine finally constructed was of the approximate dimensions, weight, and disposition of the usual conventional typewriter.

Changes and modifications are contemplated 70 within the scope of the invention as defined by the appended claims.

We claim:

1. In a printing telegraph system, a plurality of transmitting and receiving machines, each 75

machine being provided with means for the transmission and reception of electrical impulses in combination a transmitting distributor assembly and a receiving shuttle selector assembly; a transfer assembly responsive to said selector assembly; a type-bar-wheel assembly; a translator assembly operated by said selector assembly to establish selective printing positions of said type-bar-wheel assembly; means including rotatable elements for operating said transmitting distributor assembly and said receiving shuttle selector assembly in step by step unison, said means comprising an escapement mechanism, and a constant frequency device for positively actuating and controlling said mechanism.

2. In a printing telegraph machine, means including a circuit system for the transmission and reception of signalling impulses; a selecting mechanism comprising a stator incorporating marking and spacing tracks, and a track switch; a rotor provided with shuttle members, said members carrying selector legs adapted to operate in said tracks; means for progressing said rotor in definite and equidistant steps whereby said selector legs are presented in consecutive order to the operation of said switch, and whereby said selector legs are routed into either a marking or spacing track, said means comprising an escapement mechanism; and a constant frequency device for timing and positively driving said mechanism in exact phase with signalling impulses transmitted through said circuit system.

3. In a printing telegraph machine, means including a circuit system for the transmission and reception of code combinations of signalling conditions; a selecting mechanism comprising a stator and a rotor, said stator incorporating marking and spacing tracks, and a track switch, and said rotor including pivoted shuttle members; selecting legs actuated by said members and selectively operable in said tracks; means for actuating said switch whereby said selecting legs are directed into either a marking or spacing track in exact phase relation with code combinations transmitted through said circuit system, said means comprising an escapement mechanism; and a constant frequency device for timing and positively driving said mechanism.

4. In a printing telegraph system, a plurality of stations and means at each station for the transmission and reception of signalling impulses; a selecting mechanism at each station comprising a stator component incorporating marking and spacing tracks, and a track switch; a rotor component including pivoted shuttle members and selecting legs operative in said tracks and actuated by said members; a set of transfer elements; means responsive to electrical code signals and operative with said track switch to direct said selecting legs into either a marking or spacing track, and for effecting the permutative radial disposition of said transfer elements; and means for maintaining exact synchronism between electrical and mechanical processes of selection and transfer comprising an escapement mechanism; and matched reeds of constant periodicity for timing and positively driving said mechanism at each station.

5. In a printing telegraph machine, means comprising a circuit system for the transmission and reception of code combinations of signalling conditions; a shuttle selecting mechanism incorporating a pair of tracks, and including shuttle members adapted to operate in said tracks;

and means in said circuit system for orienting said members into operative position in said tracks, said means including an electro-magnetic device having its armature functioning as a switch and acting selectively in accordance with permutations of code signals transmitted in said circuit system.

6. In a printing telegraph machine, means comprising a circuit system for the transmission and reception of code combinations of signalling conditions; a shuttle mechanism incorporating a pair of tracks, and shuttle members adapted to operate in said tracks; an electro-magnetic switch for selectively actuating said members and for guiding the same into operative position into said tracks; and means for maintaining the operation of said switch in phase with said code signals, comprising an escapement mechanism; and a vibrating reed of constant periodicity for timing and positively actuating said mechanism. 20

7. In a printing telegraph machine, comprising means for the transmission and reception of signalling impulses; a selecting mechanism including a stator component incorporating marking and spacing tracks; a rotor component carrying shuttle members, said members being provided with selecting legs adapted to operate in said tracks; a track switch for selectively actuating said legs; a drive shaft, and a driven shaft carrying said rotor component; means comprising a friction clutch for coupling the drive and driven shafts; and means for causing said selecting legs to be presented in sequence for operation with said switch and at a definite rate in predetermined incremental progression, said means comprising an escapement mechanism operatively coordinated with the rotor component; and a constant frequency device for driving and timing said escapement mechanism, and independently of the rotational speed of the said drive shaft and clutch. 30

8. In a printing telegraph machine, means comprising a circuit system for the transmission and reception of signalling conditions; a selecting mechanism comprising a stator component incorporating a marking track and a spacing track; a track switch; a rotor component including shuttle members and cooperative selecting legs adapted to operate in said tracks; a corresponding set of transfer legs; means responsive to signalling conditions acting upon the progression of said rotor elements to cause said switch to direct said selecting legs into either a marking or spacing track and for simultaneously effecting permutations in the radial disposition of said transfer legs; a transfer mechanism including marking-spacing cams; and means for operatively communicating the permutations of said transfer legs to said cams in readiness to perform subsequent selective functions. 45

9. In a printing telegraph machine, means comprising a circuit system for the transmission and reception of electrical code signals; a shuttle selecting mechanism provided with a plurality of radial elements positioned for permutable operation in accordance with said signals; a transfer mechanism comprising cam members operative with said elements; an electrical translator for effecting printing and other functional operations, said translator including a plurality of electrical switches operatively connected in said circuit system; and means operatively coordinating said transfer mechanism with said selecting mechanism whereby said switches re- 70

spond to said permutable operation and in proper phase relationship with said signals.

10. In a printing telegraph machine, means comprising a circuit system for the transmission and reception of electrical code signals; a shuttle selecting mechanism provided with a plurality of radial elements adapted for permutable operation in accordance with said signals; a transfer mechanism including a plurality of pivoted cam members operatively positioned relative to said elements to receive a permuted setting from said selecting mechanism; means for operatively co-ordinating said transfer mechanism with said selecting mechanism; a translator provided with 15 slotted discs and including a plurality of push-pull bars for actuating said discs; and means for transferring said permuted setting through said bars to set said discs in marking or spacing position and in accordance with said code signals. 20

11. In a printing telegraph machine, means comprising a circuit system for the transmission and reception of electrical code signals; a selecting mechanism adapted for permutable operation in accordance with said signals, said mechanism being provided with a plurality of radial selecting elements; a transfer mechanism including a plurality of pivoted cam members operative with said elements to receive a permuted setting from said selecting mechanism; a mechanical translator having stunt bars coordinated therewith, and a restore disc operating upon said stunt bars; means for bringing the transfer mechanism into operative relation with the selecting mechanism, and simultaneously to restore said stunt bars to normal position. 25

12. A mechanism in accordance with the preceding claim, in which the mechanical translator includes a plurality of slotted code discs and push-pull bars adapted to operate therewith; and means to cause said bars to rotate said discs into either marking or spacing positions in accordance with the aforesaid permuted setting, and simultaneously to clear said stunt bars whereby any selected bar is placed in operative relation with said slotted code discs. 30

13. In a printing telegraph machine, a selecting mechanism for the reception of permutable code combinations of electrical signals comprising an electro-magnetic relay having an armature adapted to operate in response to signalling conditions; a stator component incorporating a marking track and a spacing track; a rotor component including a plurality of pivoted shuttle members provided with selecting legs adapted to operate in the tracks of said stator component; a switch actuated by said armature to cause said selecting legs to operate in said tracks selectively in accordance with said signalling conditions; and means for progressing said rotor whereby said selecting legs are assigned to marking or spacing positions consecutively and in a step-wise manner. 45

14. In a printing telegraph machine, a mechanical translator comprising a plurality of discs slotted internally in permutable relationship in respect to marking and spacing positions of said discs; a plurality of stunt bars disposed transversely of said discs and operative with said slots when in registry in accordance with a selection of one of said bars and upon a given permuted arrangement of said discs; a plurality of push-pull bars operatively coordinated with said stunt bars; a transfer mechanism comprising means for moving said push-pull bars into marking or spacing positions and for disposing the same permutable 50

with respect to said discs; means for restoring said stunt bars to normal position, and for acting upon said push-pull bars in their marking spacing movement during one-half cycle of motion of a unit assembly, which includes a transfer selection frame and a translator stunt bar control disc; and means for completing the action upon said push-pull bars in their marking-spacing movement with respect to said discs, and for freeing said stunt bars to permit a selection of said bars by said discs in the subsequent half cycle of movement of the same unit assembly.

15. In a printing telegraph machine, means for the transmission and reception of permutable code combinations of electrical signals, including a selector assembly, and a translator assembly provided with selecting elements; a transfer mechanism operative to receive a permuted setting from the selector and to transfer that setting to the selecting elements of said translator; means for restoring said selecting elements of the translator to normal in one-half cycle of motion of a unit assembly, said assembly including a transfer selection frame and translator stunt bar control disc; and means for completing the operation of the translator and for freeing the selecting elements of said translator to perform the function of selection in the subsequent half cycle of motion of the same unit assembly.

16. A printing telegraph machine, comprising a selector mechanism, a transfer mechanism, a translator mechanism, and a type wheel mechanism; means operative through said mechanisms to effect the stoppage of said type wheel in a selected printing position; means for operatively coordinating said mechanisms comprising a drive shaft having its longitudinal axis common to all of said mechanisms, and including interacting mechanical elements disposed concentrically about the same common axis.

17. In a printing telegraph machine, a keyboard transmitter mechanism, comprising in combination a plurality of keybars, a cooperating lever system including transmitting contact levers and contact elements operative to transmit permutable code combinations of electrical signals; means responsive to an equal throw of said keybars to select a permuted arrangement of said contact levers; a universal bar mechanism operative with the keybars; a release bar and means acting through said mechanism on operation of any given keybar to unlatch said release bar for establishing a mechanical arrangement in marking spacing relationship of said contact levers with respect to the said contact elements.

18. In a printing telegraph machine, a keyboard transmitter mechanism comprising a plurality of keybars; a plurality of code bars operative with the keybars in marking-spacing positions; code fingers on said keybars adapted for permutable operation with said code bars; a plurality of contact levers and corresponding contact elements operative therewith; and means for transferring the marking-spacing permutations of said code bars to control the operative relationship of said contact levers and contact elements, said means including a plurality of pawls actuated by said code bars.

19. In a printing telegraph machine, a keyboard transmitter mechanism comprising in combination a plurality of keybars each provided with code fingers; contact levers and contact elements operative therewith to transmit code combinations of electrical signals; and an intermediate lever system for operatively coordinating

5 said keybars with said contact levers, including transfer links and code bars, said bars being pivoted for balanced rotational movement about a central fulcrum and having operative engagement with said fingers and said links at pivot points in balanced relation to said fulcrum.

20. In a printing telegraph machine, a keyboard transmitter mechanism, comprising in combination a plurality of keys and keybars; a plurality of pivoted code bars selectively positioned by said keybars, and intermediate pivoted pawls positioned in turn by said code bars; transmitting contact levers and contact elements operated through the instrumentality of said pawls for the transmission of code combinations of electrical signals; and means comprising a plurality of interchangeable fingers located in permuted arrangement on said keybars and operatively engaging the said code bars to establish with each keying operation a corresponding permuted marking-spacing relationship through said code bars, intermediate pawls and contact levers.

21. In a printing telegraph machine, a keyboard transmitter mechanism comprising a plurality of keys and keybars guided for equal vertical motion; a plurality of balanced levers selectively positioned by said keybars, including a plurality of code bars carried by each keybar, and intermediate balanced levers acted upon by said last-named levers, and including transmitting contact levers, to effect a combination of electrical contacts in a signalling circuit; and means comprising a plurality of interchangeable fingers located in permuted arrangement on said keybars and operatively engaging the said code bars to establish with each keying operation a corresponding permuted marking-spacing relationship through said code bars and contact levers to establish a sequence of code signals.

22. In a printing telegraph machine, a keyboard transmitter mechanism comprising a plurality of keys and keybars; a cooperating lever system, including a plurality of balanced code bars pivotally mounted on each keybar; transmitting contact levers and corresponding contact elements for transmitting permutable code combinations of electrical signals; code extension fingers located in permuted relationship on each keybar for operative engagement with said code bars; means comprising intermediate contact pawls operative with said code bars to transfer the permuted operations of said bars to open and close said contact elements in accordance with the permuted relationship of said fingers; means for locking the contact levers in operative relation to said contact elements, said means comprising a release-restore bar provided with projections and pins carried by the said transmitting contact pawls adapted to assume locking engagement with the said projections; and means to release said locking engagement in response to subsequent operation of said bar.

23. In a printing telegraph machine, a keyboard transmitter mechanism comprising means in combination with a keyboard for the transmission of permutable code combinations of signalling impulses, said means including transmitting contacts and contact levers adapted to assume marking-spacing positions in relation to 65 said contacts; contact pawls operative with said contact levers; a release mechanism comprising a release bar operative to release said contact levers to assume marking-spacing positions with respect to said contacts, said release bar including means operative with said contact pawls to

lock up said keyboard; and means including a group of cam elements and a lever system operative therewith and with said release mechanism to restore said mechanism to normal and to unlock said keyboard.

24. In a printing telegraph machine, a keyboard transmitter mechanism comprising a keyboard and means in combination therewith for the transmission of permutable code combinations of signalling impulses, said means including transmitting contacts and contact levers adapted to assume marking-spacing positions in relation to said contacts; marking-spacing pawls operative with said contact levers; a contact lever release mechanism comprising a release bar operative to release said contact levers to assume marking-spacing positions with respect to said contacts, said bar being provided with means operative with said pawls to lock up said keyboard; and means including a pair of cams coupled in opposition, a lever system operative therewith and spring means, one of said cams functioning on one revolution to build up tension in said spring means; and a link element for communicating energy from said spring means at restore position of said cam to said release bar to restore the release mechanism to normal and to unlock said keyboard.

25. In a printing telegraph machine, a keyboard transmitter mechanism comprising means in combination with a keyboard for the transmission of code combinations of signalling impulses, said means including transmitting contacts and contact levers adapted to assume marking-spacing positions in relation to said contacts; an intermediate lever system including contact pawls operative with said contact levers; a release mechanism including a release bar functioning to release said contact levers to assume marking-spacing positions with respect to said contacts, said bar being provided with means operative with said pawls to lock up said keyboard; means including start-stop cams and a lever system operative therewith and with said release mechanism to restore said mechanism to normal; means for rotating said cams comprising a driven shaft and a prime mover differentially coupled thereto; an escapement mechanism for controlling the rotation of said driven shaft at a definite rate of progression, and independently of the speed of the prime mover; and a constant frequency device for timing and driving the escapement mechanism.

26. In a printing telegraph machine, a keyboard transmitter mechanism comprising a keyboard and means coordinated therewith for the transmission of code combinations of signalling impulses, said means including transmitting contacts and contact levers adapted to assume marking-spacing positions in relation to said contacts; intermediate pawls operative with the contact levers; a release mechanism functioning to cause said contact levers to assume said marking-spacing positions, and including means to lock up said keyboard; means including a pair of cams and a lever system operative therewith and with said release mechanism to restore said mechanism to normal; means for rotating said cams including a prime mover and a driven shaft on which said cams are mounted, said shaft being differentially coupled to said prime mover; an escapement mechanism for controlling the rotation of said driven shaft at a definite rate of progression in exact step with the processes of electrical transmission and mechanical selection, and independ-

ently of the speed of the prime mover; and a constant frequency device for timing and driving the escapement mechanism.

27. In a printing telegraph machine, means for the transmission and reception of permuted code combinations of electrical signals, including a selector assembly, a translator assembly having means including selecting elements adapted to effect and control printing and machine functions; a transfer mechanism operative to receive a permuted setting from the selector and to transfer that setting to the selecting elements of said translator; means for restoring said selecting elements of the translator to normal and thereby timing said functions in one-half cycle of motion of a unit assembly, said assembly comprising the frame of said transfer mechanism and a disc member of formed periphery; and means for completing the operation of the translator and for freeing the selecting elements of said translator to perform a new selection of functions in the subsequent half cycle of motion of the same unit assembly.

28. In a printing telegraph machine, a selector mechanism, a transfer mechanism, and a translator mechanism; means including rotatable elements for operatively coordinating said mechanisms; a drive shaft for transmitting movement to said elements, said shaft having its longitudinal axis common to all of said mechanisms; and means for controlling the predetermined progression of said elements, said means comprising an escapement which escapes the incremental progression of the selector independently of the rotational rate of said drive shaft; and a constant frequency device for timing and positively driving said escapement.

29. In a printing telegraph machine, means comprising a circuit system for the transmission and reception of code combinations of signalling conditions; a transmitting selector distributor mechanism comprising a rotary element; a receiving selector comprising a rotary element, equipped with a plurality of radially disposed fingers responsive to selecting means in said circuit system; driving means; a common driven connection between said rotary elements differentially coupled to said driving means; and means for effecting the rotation of the transmitting rotary element and the receiving rotary element simultaneously.

30. In a start-stop system of printing telegraphy, means comprising a circuit system for the transmission and reception of code combinations of signalling conditions; a rotary element for selecting transmitting conditions; a second rotary element, equipped with a plurality of extended and radially disposed fingers responsive to selecting means in said circuit system connected to said first named element for selecting receiving conditions; driving means for differentially operating said connected rotary elements; and means to effect the start-stop rotation of said elements simultaneously.

31. In a start-stop system of printing telegraphy, means comprising a circuit system for the transmission and reception of code combinations of signalling conditions; a rotary element for selecting transmitting conditions; a second rotary element operating with said first named element for selecting receiving conditions; differentially coupled driving means including a friction clutch interposed between said rotary elements; means for effecting the rotation of said rotary elements in a plurality of steps from start to stop, the

number of steps being equal to the signalling code employed, and including an escapement mechanism; and means comprising a constant frequency device for positively driving and controlling said escapement mechanism.

32. In a printing telegraph machine, means comprising a circuit system for the transmission and reception of code combinations of signalling impulses; a transmitting selector distributor mechanism comprising a plurality of conducting segments and including a rotary element selective with respect to a plurality of said segments allotted to the transmission of each impulse; a receiving selector mechanism comprising selecting members, including an electro-magnetically operated switch and a rotary element adapted to present said members to said switch when actuated in response to received signals; a power drive, and means for operatively coupling with said drive the rotary elements of said transmitting selector and said receiving selector, said means including a differential clutch to permit intermittent rotation between said sets of elements and said drive; and means for controlling the simultaneous rotation of said rotary elements of the transmitting selector and the receiving selector in predetermined progression, said means comprising an escapement which escapes the incremental progression of said rotary elements; and a constant frequency device for timing and positively driving said escapement.

33. In combination in a telegraph receiver; a set of permutation disk members; a corresponding set of reciprocating levers, and transfer elements coupled thereto for positioning said members in different combinations; a corresponding set of selectors and electromagnetic means operative therewith for selectively controlling the setting of said selectors in different combinations in accordance with received signals; a rotary member and controlling means for presenting said selectors successively to said electromagnetic means; and means including a system of cams and a camshaft carrying said cams for presenting said transfer elements to said selectors.

34. In a printing telegraph system, a plurality of transmitting and receiving stations, each station being provided with means for the transmission and reception of electrical impulses; receiving devices at each station comprising a translator assembly including a plurality of segments and a rotary brush assembly, and a continuously rotating type wheel assembly; means comprising a magnet and drive pin operated by said translator to present selected type into printing position; means including rotatable elements for operatively coordinating said assemblies; and means for maintaining step by step unison between said elements, said means comprising an escapement mechanism, and a constant frequency device which directly and mechanically actuates and controls said mechanism.

35. In a printing telegraph machine, means for the transmission and reception of permuted code combinations of electrical signals, including a selector assembly; a type wheel assembly; a translator assembly provided with selecting elements adapted to effect the stoppage of said type wheel assembly at a selected position or to select machine functions; a transfer mechanism operative to receive a permuted setting from the selector and to transfer that setting to the selecting elements of said translators; means for restoring said selecting elements of the translator to normal for releasing said type wheel into rotation,

or clearing said machine function selections in one-half cycle of motion of a unit assembly, said assembly comprising the frame of said transfer mechanism and a disc member of formed periphery; and means for completing the operation of the translator and for releasing the selecting elements to effect the stoppage of said type wheel at a new selection or the selection of a machine function in the subsequent half cycle of motion of the same unit assembly.

36. In a printing telegraph machine, means for the transmission and reception of code combinations of signalling conditions, including in combination, a type wheel assembly and driving means therefor, said assembly being differentially coupled to and concentric with said driving means; a transmitting selector comprising a rotary element; a receiving selector comprising a rotary element; a driven connection common to said rotary elements and differentially coupled to said driving means; and means to effect the rotation of the transmitting rotary element and the receiving rotary element simultaneously and independently of the rotation or non-rotation of said type wheel.

37. In a system of the character described, means for the transmission and reception of code combinations of signaling conditions, including in combination, a type wheel assembly and driving means therefor, said assembly being differentially coupled to and concentric with said driving means; a rotary element selectively responsive to transmitting conditions; a rotary element connected to said first-named element and selectively responsive to receiving conditions; means for driving said elements differentially; means for starting and stopping the rotation of said elements simultaneously and as units; and means for subsequently starting and stopping the rotation of said type wheel.

38. In a printing telegraph machine, means for the transmission and reception of code combinations of signaling conditions, including in combination, a type wheel assembly and means comprising a friction clutch drive operative to rotate said wheel from one selected stop position to another selected stop position; a rotary element selectively responsive to received conditions, and a rotary element selectively responsive to transmitting conditions, said elements being operatively coordinated; differentially coupled driving means for said rotary elements; means comprising an escapement mechanism for escaping the rotation of said rotary elements in a plurality of steps from start to stop, the number of steps being equal to the signalling code employed; and means including a constant frequency device for positively driving and controlling said escapement mechanism.

39. In a printing telegraph machine, means for the transmission and reception of code combinations of signaling conditions, including the combination, a stop at print type wheel and means comprising a differential drive for rotating said wheel from selected position to selected position, said type wheel being concentric with said drive; a receiving selector mechanism including selecting members; a rotary element, an electromagnetic switch operative with said element and responsive to received signals; a transmitting selector mechanism having a plurality of conducting segments allotted to the transmission of each impulse, and including a rotary element selective with respect to said elements; a power drive, and means differentially coupled thereto for rotating the rotary elements of said receiving selector and

said transmitting selector, said selectors being concentric with the type wheel; and means for controlling the simultaneous rotation of said rotary elements of the receiving selector and the transmitting selector in predetermined progression independently of the rate of rotation of said type wheel, said means comprising an escapement which escapes the incremental progression of said rotary elements; and a constant frequency device for timing and positively driving said escapement.

40. In a printing telegraph machine, a selector mechanism, a transfer selection mechanism, and a permutation disc translator mechanism; a type-wheel assembly comprising a frame housing; a drive mechanism, including a drive shaft and friction clutch located internally of said housing; a type wheel coupled for differential rotary movement relative to said drive shaft; and a plurality of pivoted type bars carried by said wheel, being radially disposed about the axis of said drive shaft and externally of said housing, each of said bars being formed as a bell crank lever; actuating means for said type bars in selected position; means for stopping the said type wheel at the selected position, comprising transverse members of said translator mechanism whereby the selected type bar is presented for printing operation by said actuating means, and including a stop member on said type wheel which engages said transverse members of said translator mechanism in off normal position, and in which said type wheel is concentric with and directly above said translator mechanism; and means for bracing said transverse members in radial slots close to the point of impact of said stop members.

41. In a printing telegraph machine, means for the transmission and reception of code combinations of signaling conditions; a transmitting selector mechanism; a receiving selector mechanism; a type wheel mechanism including pivoted type bars, and means to present said bars to a selected position; a cam and lever mechanism operative to actuate the selected type bar into printing position; means for operatively coordinating said mechanisms with one other; means for guiding said selected type bar through to said printing position; and means for returning said type bar to normal position sharply, comprising a spring acting common to all type bars.

42. In a printing telegraph machine, a type wheel assembly and a housing therefor; a drive mechanism, including a drive shaft and friction clutch located internally of said housing; a type wheel coupled through said clutch for differential rotary movement relative to said drive shaft; and a plurality of pivoted type bars carried by said wheel, being radially disposed about the axis of said drive shaft as a common center and externally of said housing, each of said bars comprising a character component and an actuating component formed as a lever; actuating means for said type bars in selected printing position; and means to permit replacement of said type wheel assembly as a complete unit by another similar unit bearing different type bar character components.

43. A combination in accordance with the preceding claim, in which said character component of said type bars includes separate character platens adapted for alternative printing in selected positions.

44. In a printing telegraph machine, including a selector responsive to electrical code conditions,

a code disk translator, a paper platen, a printing ribbon; a type wheel assembly comprising a plurality of pivoted type bars mounted for rotational movement about a common axis from a selected stop position to the next selected stop position of said code disk translator, there being no normal stop position of the type wheel; actuating means for bringing said type bars into contact with said paper platen with said printing ribbon interposed; means including cam and spring elements to effect the operation of said type bar actuating means; and means comprising a single spring member to return the operated type bar to normal.

15 45. In a printing telegraph machine, including a selector responsive to coded electrical signals and a slotted code bar translator; a type wheel assembly comprising a plurality of pivoted type bars mounted for rotational movement about a common axis; means for step-by-step operation of individual type bars; actuating means for said bars including a hammer pivoted for operative movement in the arc of a circle, and means including cam elements to effect the return movement of said hammer; and means operative with said hammer to utilize the return movement of the hammer in the performance of machine functions.

30 46. In a printing telegraph machine including a selector responsive to coded electrical signals and a slotted code bar translator; a type wheel assembly comprising a plurality of pivoted type bars mounted for rotational movement about a common axis; means for step-by-step operation of individual type bars; a recording surface; and means for actuating said bars into impression upon said recording surface, said means including a pivoted hammer; means including cam elements to operate said hammer; and means operative with said hammer and responsive to the return movement thereof to advance said recording surface.

45 47. In a printing telegraph machine responsive to code combinations of electrical signaling conditions; a keyboard assembly having a signaling contact and lever system coordinated therewith, and said assembly including keybars coded in a particular sequence of characters, the assembly being operative to establish permutations in a plurality of permutation elements presented to said contact and lever system; and means for removing the keyboard assembly including the permutation elements as a unit from the association with the signaling contact and lever system in order to replace said assembly with a similar keyboard coded in another assignment of characters.

60 48. In a printing telegraph machine, a keyboard transmitter mechanism comprising a plurality of keybars; a plurality of code bars operative with the keybars in marking-spacing positions; code fingers on said keybars adapted for permuted operation with said code bars; a plurality of contact levers and corresponding contact elements operative therewith; means for transferring the marking-spacing permutations of said code bars to control the operative relationship of said contact levers and contact elements, said means including a plurality of pawls actuated by said code bars; and means for removing the assembly of keybars, code bars, and code fingers, as a unit from the association with the contact levers and contact elements.

GEORGE A. GRAHAM.
HARRY W. PARMER.
